W. E. Arnold,
Sash Fastener.
No. 12,710. Patented Apr. 17, 1855.

Inventor:

W. E. Arnold

UNITED STATES PATENT OFFICE.

WILLIAM E. ARNOLD, OF ROCHESTER, NEW YORK.

SASH-FASTENER.

Specification of Letters Patent No. 12,710, dated April 17, 1855.

To all whom it may concern:

Be it known that I, WILLIAM E. ARNOLD, of Rochester, in the county of Monroe and State of New York, have invented certain 5 new and useful Improvement in Sash-Locks, of which the following is a full and exact description, reference being had to the accompanying drawings, making part of this specification, and to the letters of reference 10 marked thereon, the same letters referring to like parts in all the drawings, and of said drawings—

Figure 1 is a perspective view of the lock as attached to a sash stile. Fig. 2 is a plan 15 of the case or box of the lock. Figs. 3 and 3' show the slide which moves the bolt in plan and cross section. Fig. 4 shows the form of the bolt. Figs. 5 and 7 exhibit the different modes of arranging the bolt and 20 slide so as to answer for either a right or left hand lock. Figs. 6 and 7 are intended to explain that feature of this combination which renders it difficult or impossible to operate the bolt when fully ejected, by simply 25 pressing upon the projecting end B Fig. 1.

The nature of my invention consists in so 30 constructing and arranging a movable slide operating a bolt within a case or box that the bolt may be easily reversed so as to form either a right or left hand lock at pleasure; and further the arrangement is such that no 35 pressure on the point of the bolt in the direction of the arrow (Fig. 1) can move said bolt when fully ejected and push it into the case. In order to accomplish this I construct a bolt of the form shown in Fig. 4 and a slide shown in plan and cross section in 40 Figs. 3 and 3'. The bolt lies on the slide as seen at B Figs. 5, 6 and 7. When in the position shown in Figs. 6 and 7 it will form a left hand lock; but when in the position shown in Fig. 5 or simply reversed it will form a right hand lock. Corresponding slots are of course cut in the case to adapt

it to these different positions of the bolt as 45 seen at s, s, Figs. 1 and 2.

D is a knob or handle for operating the slide and bolt through the slot d, Figs. 1 and 2.

It is evident that as the motion of the bolt 50 is produced by the motion of the slide through the circular wedge W on said slide any force applied to the bolt will, under some circumstances affect the slide. In the arrangement described and shown however 55 when the slides falls down so that the center of the curve which forms the wedge is nearly on or below the point of the bolt any pressure endwise on the bolt will merely press the slide against the opposite side of the 60 case but can produce no vertical motion whatever. This is clearly seen from an inspection of Fig. 7. As the slide is raised however the direction of pressure on the wedge becomes more and more nearly vertical until when the slide reaches the top of 65 its travel the direction of pressure on it is such that it yields to any pressure on the bolt. And thus while all risk of accident from the sash falling on account of worn 70 stops or ill-fitted casings is avoided, there is no danger of tearing or injuring the casing while the sash is in motion. The latter feature is very easily understood from an inspection of Fig. 6.

Having thus fully described my invention what I claim as new and desire to secure by Letters Patent is—

The mode, substantially as herein set forth, of constructing and arranging a slide, 80 bolt and case so as at pleasure to form either a right or left hand lock—the security also of said lock being attained by means substantially as described.

WM. E. ARNOLD. [L.S.]

Signed in presence of—

JOHN PHIN,

H. G. ARNOLD.
